FEEDING MECHANISM FOR ROCK DRILLS

Albert Feucht, Garfield Heights, Ohio, assignor
to The Cleveland Rock Drill Company, Cleve-
land, Ohio, a corporation of Ohio

Application March 21, 1939, Serial No. 263,155

9 Claims. (Cl. 255—45)

This invention relates broadly to rock drills, but more particularly to a feeding mechanism for rock drills of the drifter type.

One object of this invention is to produce a 5 rock drill with a feeding mechanism actuated by virtue of the jars imparted to the drill during normal operation.

Another object of this invention is to produce a 10 rock drill with a feeding mechanism of simple construction forming a compact assembly which is strong, durable and efficient.

Other objects and advantages more or less 15 ancillary to the foregoing reside in the specific construction and aggroupment of the elements 15 peculiar to this structure, as will become apparent from a more complete examination of this specification.

In the drawings:

Fig. 1 is a longitudinally side elevational view 20 of a rock drill embodying the invention.

Fig. 2 is a top plan view of the rear end portion 25 of the rock drill shown in Fig. 1.

Fig. 3 is an enlarged cross sectional view taken 30 through a plane indicated by line 3—3 in Fig. 1.

Fig. 4 is a view corresponding to Fig. 1 of the 35 feeding mechanism illustrating parts in a different position.

Fig. 5 is a longitudinally sectional view taken 40 in a plane indicated by line 5—5 in Fig. 2.

Fig. 6 is an enlarged cross sectional view taken 45 in a plane indicated by line 6—6 in Fig. 3.

Figs. 7, 8 and 9 are views similar to Fig. 6 illustrating movable parts in different positions.

Fig. 10 is an enlarged cross sectional view taken 50 in a plane indicated by line 10—10 in Fig. 1.

Fig. 11 is a longitudinally sectional view taken 55 in a plane indicated by line 11—11 in Fig. 1.

Referring to the drawings; 20 represents the 60 usual support having a drill 21 longitudinally slidable thereon. In the present construction, the drill instead of being formed with the usual guideways integral therewith for guided slidable engagement on the support, is detachably secured on a cradle 22 by clamps 23, one of which is 65 shown in Fig. 1, which clamps preferably fit on the drill's rod 24, while the head 25 of the drill is provided with two rearwardly extending lugs 26 located between corresponding lugs 27 extending 70 upwardly from the cradle 22 and detachably secured thereto by a cross bolt 28. In this construction, the drill 21 and cradle 22, when mounted as shown in Fig. 1, constitutes a drilling apparatus of the drifter type wherein the drill may be removed from the cradle and used as a 75 hand supported drill. The cradle 22 is of course

formed with the usual guideways 22' fitted over the support for free slidable guided movement thereon. Below each lug 27, the cradle is formed with a longitudinally apertured boss 29 each accommodating the head 30 of a bolt 31 extending 5 longitudinally therefrom through a similar boss 32 also formed integral with the cradle, which bolt is held in place by a nut 33 engaging the boss 32. Slidable on each bolt 31, there is a guideway 34 formed integrally with a feed motor 10 housing 35 located above the cradle 22. The guideways 34 are shorter than the longitudinal space between the cradle-bosses 29 and 32 to enable relative longitudinal movement therebetween, and are normally maintained against 15 the bosses 32 by compression springs 36 interposed between the ends of the guideways 34 and heads 30 of the bolts 31.

Within the casing 35, there is a sprocket wheel 20 or feed element 37 rotatable within a longitudinal vertical plane relative to the support. On one side the wheel 37 is formed with a shafted portion 38, and on the other side with an enlarged ring 39, both being adequately journaled within the housing 35. Passing over the sprocket 25 wheel 37, there is a chain or feed member 40 having one end secured to the rear end of the support 20 by a bolt 41, and the other end to the front end of the support by a tension adjusting bolt 42. To maintain the chain 40 in operative 30 engagement with a major portion of the sprocket wheel 37, there are two rollers 43 and 44 engaged by the chain as clearly shown in Fig. 5.

Internally, the ring 39 is formed with V-shaped 35 teeth 45, the purpose of which will be explained later. Inside of the ring 39, there is a stationary head 46 formed with a shank 47 extending through the housing and held in position by a nut 48. The head 46 has two branches 49 and 50, the former carrying a pawl 51 engageable 40 with one side of the teeth 45, and the latter carrying a similar pawl 52 engageable with the other side of the teeth 45. The two pawls 51 and 52 are constantly urged outwardly, each by a spring pressed plunger 53. Rotatable within the shank 47 of the head 46, there is a stem 54 having its free end extending out of the housing 35 to receive one end of a vertical link or lever 55 secured thereon against rotation by a key 56 and against endwise movement by a nut 57. On 50 its other end, the stem 54 is provided with a pendulum or oscillable member 58 located within the ring 39 and extending radially of the head 46. This pendulum also carries a pawl 59 constantly urged into engagement with one side of 55

the teeth 45 of the ring 39 by a spring pressed plunger 60.

Also mounted within the casing 35 for rotation relative to the ring 39, there is a pawl operating circular plate 61 formed with an annular marginal bead 62 engageable with a portion of the pawls 51, 52 and 59, which extends beyond the adjacent end of the ring 39. This annular bead is provided with two radially disposed slots 63 and 64, the former enabling engagement of the pawls 51 and 52 and the latter of the pawl 59 with the teeth 45 of the ring 39. This plate is rotatable through a handle 65 located on one side of the housing 35 and having a stem 66 within the housing ending adjacent the plate 61. This stem 66 is connected to the plate 61 by a pin 67 located in eccentric relation with respect to the center axis of the stem in a manner effecting rotation of the plate upon rotation of the handle 65.

The vertical link 55 is provided with a trunnion 68 having pivotally mounted thereon one end of a horizontal link or lever 69, which link has its other end pivotally connected to one of the lugs 27 of the cradle 22 by a cross bolt 70.

In the operation of the device, when the rock drill 21 has motive fluid admitted therein for reciprocating its piston in the usual manner, the reversal of the piston's stroke in the rock drill will impart forward and backward jars or reciprocatory motion to the drill and consequently to the cradle 22 relative to the support 20. When it is desired to feed the drill toward the work, the handle 65 may be rotated to position the plate 61 as shown in Figs. 7 and 8. In this instance, the pawls 52 and 59 located within the slots 63 and 64 respectively are engageable with one side of the teeth 45 of the ring 39. During the rearward jars of the rock drill 21, the sprocket wheel 37 engaging the chain 40 will tend to rotate in a clockwise direction in Fig. 5, which rotation is prevented by the engagement of the pawl 52 with the teeth 45 of the ring 39, thereby maintaining the housing 35 stationary relative to the support 20. During this rearward movement of the rock drill, its cradle 22 will move therewith to compress the springs 36. In this instance, the vertical link 55 connected to the cradle by the horizontal link 69 will be moved from the position in Fig. 1 to the position in Fig. 4, thus effecting movement of the pendulum 58 from the position in Fig. 7 to the position in Fig. 8. As the rock drill is moved forwardly during its forward jars, the energy stored within the springs 36 will cause the cradle 55 together with the drill to move forwardly relative to the housing 35, thereby imparting rotation to the pendulum 58 from the position in Fig. 8 to the position in Fig. 7. Due to the operative engagement of the pawl 59 with the teeth 45 of the ring 39, this ring will be rotated by the pendulum in a counterclockwise direction in Fig. 8, resulting in the rotation in the same direction of the sprocket wheel 39 for imparting feeding motion to the rock drill due to the operative engagement of the sprocket wheel with its stationary chain 40. During this forward movement of the rock drill, it will be understood that after the energy stored within the springs 36 has been dissipated, the bosses 32 of the cradle engaging the guideway 34 of the housing 35 will also impart forward movement to the housing resulting in the rotation of the sprocket wheel 39 in a counterclockwise direction in Fig. 5, which rotation is not prevented by the engagement of the pawl 52 with the teeth 45 of the ratchet ring 39.

Consequently, it is clear that the swinging movement of the pendulum 58 results in a feeding motion of the rock drill additional to that normally transmitted thereto by virtue of the engagement of the cradle bosses 32 with the guideways 34 of the housing 35, which engagement is responsive to the normal forward jars of the drill.

When it is desired to feed the rock drill away from the work, the handle 65 may be rotated to position the plate 61 as shown in Fig. 9. In this instance, the pawl 59 of the pendulum 58, together with the pawl 52 of the head 46, is maintained out of engagement with the teeth of the ratchet ring, while the pawl 51 now located within the slot 63 is engaging the other side of the ratchet ring teeth 45. The backward jars of the rock drill transmitted to the cradle 22 will in turn be transmitted to the housing 35 by the compression springs 36, thereby causing the sprocket wheel 37 due to its engagement with the stationary chain 40 to rotate in a clockwise direction in Fig. 5. In this instance, rotation of the sprocket wheel 37 in a counterclockwise direction in Fig. 5 by virtue of the forward jars of the drill, is prevented by the engagement of the pawl 51 with the ratchet ring teeth 45. Consequently, it will be understood that the rearward jars of the rock drill are utilized to cause intermittent rotary motion of the sprocket wheel 37 in a clockwise direction in Fig. 5, resulting, due to the operative engagement of the sprocket wheel 37 with the chain 40, in a step by step rearward feeding motion of the rock drill 21.

When it is desired to lock the rock drill 21 on the support 20, the handle 65 may be rotated to position the plate 61 as shown in Fig. 6. In this instance, the pawls 51 and 52 located within the slot 63 are capable of engagement with opposed sides of the teeth 45 of the ratchet ring 39, thereby preventing rotation of the ring and consequently of the sprocket wheel 37 in either direction and causing the rock drill to be locked to the chain 40 against movement relative to the support 20.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a drilling apparatus, the combination of a support, of a drill slidable on the support having reciprocatory motion imparted thereto, of a rotatable feed element carried by the drill, of means on the support operatively associated with said element whereby its rotation results in the feeding motion of the drill, connecting means between the drill and the feed element enabling limited reciprocatory motion of the drill relative to the element, and means deriving motion from said relative reciprocatory motion for actuating said member.
2. In a drilling apparatus, the combination of a support, of a drill slidable on the support having reciprocatory motion imparted thereto, of a feeding mechanism for the drill including a feed element associated with the drill for slidable movement therewith and capable of rotation for imparting feeding motion thereto, connecting means between the drill and said element enabling relative reciprocatory motion therebe-

tween, and means deriving motion from said relative reciprocatory motion for actuating said element.

3. In a drilling apparatus, the combination with a support, of a drill slideable on the support having jars imparted thereto, of a feeding mechanism for the drill including a feed member secured to and extending longitudinally of the support, a rotatable feed element connected to the drill for limited longitudinal reciprocatory movement relative thereto resulting from said jars, said element being operatively associated with said member for imparting feeding motion to the drill upon rotation of said element, and means deriving motion from said relative longitudinal reciprocatory movement for rotating said element.

4. In a drilling apparatus, the combination with a support, of a drill slideable on the support having jars imparted thereto, of a feeding mechanism for the drill including a feed member secured to and extending longitudinally of the support, a rotatable element carried by the drill operatively associated with said member for effecting feeding motion of the drill upon rotation of said element, connecting means between the drill and said element enabling limited relative longitudinal movement therebetween resulting from said jars, and means deriving motion from said relative longitudinal movement for rotating said element.

5. In a drilling apparatus, the combination of a support, of a drill slideable on the support having reciprocation imparted thereto relative to the support, of a feeding mechanism including a housing on the support capable of slideable movement relative thereto, a rotatable element in said housing, of means on the support operatively associated with said element whereby rotation of said element results in the feeding motion of the drill, spring means between the drill and the housing enabling limited reciprocatory movement of the drill relative to the housing, said spring means having energy stored therein by virtue of said relative movement in one direction, and lever means operatively associated with said element responsive to the energy stored within said spring means for rotating said element.

6. In a drilling apparatus, the combination of a support, of a drill slideable on the support having reciprocatory motion imparted thereto relative to the support, of a feed mechanism including a housing, a rotatable element and an oscillable member within said housing, rotation transmitting means between said member and element whereby oscillatory motion of the former results in a step by step rotary motion of the

latter, means on the support operatively associated with said element whereby its rotation results in the feeding motion of the drill, connecting means between the drill and the housing enabling limited reciprocatory movement of the drill relative to the housing, and means deriving motion from said relative movement for imparting oscillatory movement to said member. 5

7. In a drilling apparatus, the combination with a support having a drill slideable thereon, of a feeding mechanism including a chain secured to and extending longitudinally of the support, a sprocket wheel carried by the drill operatively engaging said chain, connecting means between said drill and sprocket wheel enabling limited relative longitudinal movement therebetween, said drill having jars imparted thereto effecting said relative longitudinal movement, and means deriving motion from said movement for imparting intermittent rotation to said sprocket 20 wheel in one direction.

8. In a drilling apparatus, the combination of a support, of a drill slideable on the support having reciprocatory motion imparted thereto relative to the support, of a housing carried by the support for slideable movement relative thereto, a rotatable element and a swingable member within said housing, means extending longitudinally of the support operatively associated with said element whereby its rotation effects feeding movement of the drill, connecting means between said element and member effecting rotation of the element upon swinging motion of the member, connecting means between the drill and housing enabling limited relative reciprocation therebetween, and means deriving motion from said relative reciprocation for imparting swinging motion to said member. 30 35

9. In a drilling apparatus, the combination of a support, of a drill slideable on the support having reciprocatory motion imparted thereto relative to the support, of a feeding mechanism for the drill including a housing carried by the support for slideable movement relative thereto, a feed member extending longitudinally of the support, 40 an element within said housing capable of a predetermined motion, said element being operatively associated with said member whereby the predetermined motion of the former relative to the latter results in the feeding motion of the 50 drill, connecting means between the drill and said housing enabling limited relative reciprocation therebetween, and means deriving motion from said relative reciprocation for imparting said predetermined motion to said element. 55

ALBERT FEUCHT.
